US0D1053879S

(12) **United States Design Patent** (10) Patent No.: **US D1,053,879 S**
(45) Date of Patent: **** Dec. 10, 2024**

(54) **EARPHONE JACK**

(71) Applicant: **Dreamus Company**, Seoul (KR)

(72) Inventor: **Jong Min Jeong**, Seoul (KR)

(**) Term: **15 Years**

(21) Appl. No.: **35/519,946**

(22) Filed: **Sep. 6, 2023**

(80) **Hague Agreement Data**

Int. Filing Date: **Sep. 6, 2023**

Int. Reg. No.: **DM/234628**

Int. Reg. Date: **Sep. 6, 2023**

Int. Reg. Pub. Date: **Feb. 2, 2024**

(51) **LOC (14) Cl.** **14-02**

(52) **U.S. Cl.**
